CHANGE SPEED MECHANISM

Samuel E. Secoy, Newcastle, Ind., assignor of
one-half to Hiram L. Smith, Newcastle, Ind.

Application February 15, 1933. Serial No. 656,785

5 Claims. (Cl. 74—14)

This invention relates to improvements in change-speed mechanisms. The object of the invention is to provide a device of the above description which is quiet in operation, durable, and dependable. Other and more specific purposes of the invention are to provide a mechanism which is economical of manufacture, and which is of structure to lend itself to uses of wide range.

10 The aims of my invention are accomplished by, and the invention is embodied in the new construction, combination and arrangement of parts illustrated in the accompanying drawing, and described in the following specification.

15 The several parts of the invention are identified by suitable characters of reference applied to them in the different views in the drawing, in which—

20 Figure 1 is a vertical central sectional view of my improved change-speed mechanism, a portion of the wall of the casing, and certain of the parts, and portions of parts, being shown in elevation.

25 Figure 2 is a sectional plan view, on the line 2—2, looking upwardly in the direction of arrow 2 in Figure 1.

Figure 3 is a sectional plan view, on the line 3—3, looking upwardly in the direction of arrow 3 in Figure 1.

30 Figure 4 is a sectional plan view, on a reduced scale, on the line 4—4, looking upwardly in the direction of arrow 4 in Figure 1.

Figure 5 is a sectional plan view, on a reduced scale, on the line 5—5, looking upwardly in the direction of arrow 5 in Figure 1.

Figure 6 is a sectional plan view, on a reduced scale, taken on the line 6—6, looking downwardly in the direction of arrow 6 in Figure 1.

40 Figure 7 is a sectional plan view, on a reduced scale, on the line 5—5 in Figure 1, looking downwardly in the direction of arrow 7.

A typical embodiment of the invention, and one that is intended to effect a substantial change of speed between the driving element and the driven element, is illustrated in the drawing, it being understood that minor changes and modifications of the several parts may be made, within the scope of the invention as same is defined in the appended claims, without departing from the spirit of the invention.

45 In the following description, it will be assumed that the longitudinal axis of the mechanism is vertical; that the driven element is the one that moves at the lower speed; and that the side of the casing through which the driven element

projects, is the top of the device. The invention is capable of being practiced in the embodiments of various sizes and for divers purposes. When intended for use in power plants for motor vehicles, pumping machinery, and like installations, an embodiment of relatively small size, such as the one herein illustrated wherein the casing is about eight by eight inches in inside dimensions, may be used.

50 The driving element, designated as driving shaft 1, has the integrally formed disk shaped head 2 and it is rotatably mounted in ball bearing 3 which is seated in wall 4 that constitutes a part of the casing. On the bottom face of said head is annular ball bearing retaining the 60 balls 6 which roll in race 7 provided therefor upon the inner face of casing wall 4.

55 On a line diametric of head 2 and spaced equidistant from the axial center of said head, are semihemispherical sockets. Disposed in the said 70 sockets are steel balls 10 and 11, as shown in Figure 6.

60 A rotor which consists of a cylindrical body 11 is provided with a peripheral groove which provides bearing ways or faces 12, 13, and 14. The axial center of the rotor is coincident with the center of ball 10, and at its bottom face are diametric runways 15 and 16 which are at right angles to each other. On the top face of the 80 rotor on a diametric line which is at a right angle to the diametric line upon which are located the balls 10 and 11, are provided spaced semi-hemispherical sockets. In these sockets are disposed steel balls 18 and 20.

65 The driven member, designated as driven shaft 21, embodies a disk shaped head 22. Provided on the bottom of said head 22 are diametric runways 23 and 24, at a right angle to each other, and at an angle of forty-five degrees to the afore- 90 said runways 15 and 16.

70 Balls 25 of annular anti-friction bearing which is provided on the top face of the head 22 have bearing in a suitable race provided therefor on the inner face of the casing wall 26.

75 A divided frame consists of sections 31 and 32, whose heads are united by bolts 33 and 34. This frame is provided with a bore 35 which is of diameter slightly larger than the diameter of the rotor and it has a central integral ring shaped shoulder 36. In each side of said shoulder are spaced transverse circular recesses 37 which extend to the center of said shoulder. The positions of the recesses of one side of said shoulder are alternated with the positions of the recesses of the other side of the said shoulder.

105

110

Seated in the said recesses are balls 39 and 40. The axial centers of these recesses are such that the peripheral faces of the balls protrude slightly beyond the periphery, and 5 slightly beyond the sides of the said shoulder.

United with said frame sections 31 and 32 are plates 42 and 43 which constitute the end walls of the casing. It will be observed that the base portion of section 32 is sufficiently longer 10 than the base portion of the base of section 31 that the center of the ring shaped bore 35 of said frame is eccentric to the axial center of the said driving shaft and said driven shaft, and the axis of the rotor is coincident, as hereinbefore stated, with the center of ball 10.

It will be understood that in processing the frame, the sections thereof are bolted together at the machined faces of the heads, and then there is machined the bore 35 and annular 20 shoulder 36. To assemble the mechanism, the said frame sections 31 and 32 are first taken apart by removing the bolts 33 and 34. Balls 39 and 40 are then disposed in the recesses 37 at each side of said shoulder 36. At this stage, the 25 said balls may be retained against easy dislodgement by a packing of cup grease at the said recesses. The frame sections are then disposed in position, their head portions being in engagement, and the balls 39 and 40 being in position 30 in the raceway groove of the rotor 11. At the same time, the casing plates 42 and 43 will have been brought into engagement with the ends of the bottom and top plates 4 and 26 respectively. They are then secured by cap screws 45. Lastly, 35 the casing plates 46 and 47 are placed in position and they are secured by cap screws 48 and 49. The head portions of the frame may be stayed by cap screws 50 that are passed through the casing plates 46 and 47.

40 Operation of the invention will be understood by referring to the drawing. The balls 10 and 11 function in the manner of wrists, transmitting power from the head 2 to the rotor as they roll in the runways 15 and 16. In the embodiment 45 shown, there are two revolutions of the rotor, during a single revolution of the driving head 2. The rotor having the balls 18 and 20 and which are operable in the runways 23 and 24 of the head 22, there is a step-up of two revolutions of the 50 head 22 for each revolution of the rotor. Further increase in the differential of speed between the shafts may be had by the addition of a rotor member adapted to be actuated by member 22.

Suitable lubricant introduced at the inlet 54, 55 and which is retained in the casing, affords lubrication for all of the bearing parts and surfaces. Discharge of said lubricant for refilling, is had at the outlet 55.

A mechanism constructed according to my invention is strong, durable and close-built. It lends itself to easy modification in form, size and proportions, and its several parts are firmly retained in true alignment and against vibration, and against the most severe driving, torque and thrust strains. The several moving parts receive ample and uniform lubrication, and the device operates practically noiselessly and with a minimum of friction. In installations where the driven shaft is the one that is intended to be operated at the lower speed, the position of the mechanism as a whole is reversed, the power for driving, being applied to shaft 21. There now results a speed reduction, there being eight revolutions of the shaft 1, during a single revolution 70 of the shaft 21. The device occupies a minimum

of space, and it is practicable of operation either in vertical or horizontal position, or in any position of incline. It will be understood that the proportions and dimensions of the several working parts, and the mounting thereof, and the 80 detail formation of the several anti-friction bearings, may be modified to accord with various conditions, and methods of processing, without departing from the principles of my invention and that the invention is to be construed as being 85 of breadth and scope in conformity with the language of the following claims.

What I claim as my invention is—

1. A change-speed mechanism, comprising opposed proximate rotatable members in offset axial alignment, the head of one having projecting diametrically opposed anti-friction power transmitting members spaced equidistant from the axial center of said head, and the head of the other rotatable member having diametric grooves at 95 right angles to each other, the axial center of said head being coincident with the center of one of the said power transmitting members, and one of the grooves being in engagement with the said power transmitting members. 100

2. A change-speed mechanism, comprising opposed headed rotatable members in offset alignment, the head of one having diametrically opposed semi-hemispherical sockets spaced equidistant from its center, a ball in each socket, and the head of the other rotatable member having diametric grooves at right angle to each other, one of which engages said balls, and the center of said last named rotatable member being coincident with the center of one of said balls. 110

3. A change-speed device comprising a frame, opposed headed members mounted for rotatable movement but which are held against longitudinal movement in said frame, the said members being in offset alignment and the head of one having diametrically opposed semi-hemispherical sockets equidistant from its center, a ball in each of said sockets, and the head of the other rotatable member having diametric grooves semicircular in cross section and at right angles to each other, one of which engages said balls, and the center of said last named rotatable member being coincident with the center of one of the said balls. 120

4. A change speed mechanism, comprising opposed rotatable members in offset alignment one 125 having diametrically opposed semi-hemispherical sockets spaced equidistant from its center, a ball in each socket, and the other rotatable member having diametric grooves at right angle to each other one of which engages said balls, and the axis of said last named rotatable member being coincident with the axis of one of the balls and the other side of said last named rotatable member having diametrically opposed semi-hemispherical sockets spaced equidistant from its center, a ball in each socket, a third rotatable member 135 in axial alignment with the first named rotatable member and which is provided with diametric grooves at right angle to each other, one of which said grooves engages the said last named 140 balls.

5. A change-speed mechanism, comprising a casing having opposed wall plates, confronting headed members journaled in said wall plates in axial alignment, one of said headed members having diametrically opposed semi-hemispherical sockets spaced equidistant from its center, and the other of said headed members having diametric runway grooves at a right angle to each other, a frame embodied in said casing, a rotor 145

journaled in said frame for rotative movement but held against longitudinal movement, and whose axis is offset from the axis of said headed members, one side of said rotor having diametrically opposed semi-hemispherical sockets spaced equidistant from its center, and the other side of said rotor having diametric runway grooves at a right angle to each other and one of which is in alignment with the said sockets, balls in the aforesaid sockets, and frame connections between the wall plates of the casing, to hold the said headed members against longitudinal movement. 80
